Willis H. Jordan

UNITED STATES PATENT OFFICE.

WILLIS H. JORDAN, OF BOSTON, MASSACHUSETTS, ASSIGNOR TO COLONIAL SCALE COMPANY, OF BOSTON, MASSACHUSETTS, A CORPORATION OF MAINE.

LIFTING-MACHINE.

SPECIFICATION forming part of Letters Patent No. 712,072, dated October 28, 1902.

Application filed July 9, 1901. Serial No. 67,655. (No model.)

To all whom it may concern.

Be it known that I, WILLIS H. JORDAN, of Boston, in the county of Suffolk and Commonwealth of Massachusetts, have made certain new and useful Improvements in Coin-Controlled Lifting-Machines, of which the following is a description sufficiently full, clear, and exact to enable any person skilled in the art or science to which said invention appertains to make and use the same, reference being had to the accompanying drawings, forming part of this specification, in which—

Figure 1 is a front elevation of a coin-operated weighing-scale, showing my improved lifting device; and Fig. 2, a vertical section through the lifting-handle and contiguous parts.

Like letters of reference indicate corresponding parts in both figures of the drawings.

My invention relates especially to an attachment for coin-controlled weighing-scales whereby lifting strain may be indicated in the same dial as is the weight and by the same weighing mechanism.

This present invention is designed particularly as an improvement on the device shown in my application for United States Letters Patent, Serial No. 44,471, filed January 23, 1901.

In carrying out my invention I make use of means which will be readily understood by those conversant with such matters from the following explanation.

In the drawings, A represents the body or casing of the weighing-machine, which consists of a hollow shaft surmounted by a dial B, provided with index f. Above this is the coin-slot g. At the base of the column is the scale-platform h. This is mounted on the balance-levers and operates the coin-released spring-balance weighing mechanism contained in the body or column and actuating the index f in the usual manner. As these parts are all of ordinary construction, it is not deemed essential to illustrate or describe the same in detail, as they have no direct bearing on my present invention, which is applicable for use with any weighing-machine of this class.

In lugs k on the base of the column A is fitted to rotate a vertical rod j, carrying a frame

C, of any ornamental design, on the outer edge of which is formed a vertical tube m. As thus arranged this frame may be swung horizontally back against the column-base or out over the platform h.

Projecting laterally from the frame-tube m there is a hollow foot v, and fitted to slide vertically within said tube there is a lifting-tube s, provided adjacent its lower end with a slot y, which registers with the inner end of said foot v. In this foot is pivoted to swing vertically a lever w, with a downwardly-turned nose x, disposed in position to be thrown into contact with platform h, as hereinafter described. The inner end of this lever projects through the slot y of tube s and between two pins z z, passing through said tube, the distance between these pins being sufficient to admit slight lost motion before engaging the lever-arm.

The lifter-tube s has an enlarged head t overlapping the top of tube m and limiting the downward movement of said lifter-tube therein. Into this head is turned the thread end r of a lifting-handle p, its head q being at right angles to said bar in the usual manner.

The lever w is pivoted centrally between point of contact with lower pin z and of its nose x with platform, so as not to afford aiding leverage to operator.

Formed integral with or secured to the frame of the platform h and projecting horizontally therefrom respectively at opposite sides there are wings or foot-plates i i.

In the use of my invention the scale is employed for weighing persons or articles on the platform h in the usual manner, the balance mechanism being released by the insertion of coin in chute g. As this is common and well known to all versed in the art, its particular description is deemed unnecessary. When it is desired to test the lifting strength, he steps astride the platform h, his feet resting, respectively, in the wings i i. The frame C is swung forward until the lever-nose x is over the platform. The handle p is adjusted at the convenient height by means of its threaded ends. Lifting strain being applied to the handles, the scale mechanism having been previously released by the insertion of a coin in chute g,

the nose x of lever w is driven against platform h as lifter-tube s is thus drawn upward. The platform h is thereby depressed in the same manner as when weight is applied there-
5 to, and the amount in pounds will be indicated on dial B , as will be evident to those conver-
sant with such matters without a more ex-
plicit description.

It will be seen that by providing the wings
10 i for operator to stand on it is not necessary
to fasten the mechanism to the floor, and the
strain on the frame is greatly relieved. More-
over, by this means I thereby avoid the ne-
cessity of deducting the weight of person op-
15 erating the device from the indicated lift, as
is necessary when the operator stands on the
scale-platform, or else the providing of mech-
anism for compensating for this weight would
be necessary.

20 Having thus explained my invention, what
I claim is—

1. A scale mechanism provided with a plat-
form in combination with a lifting-handle ad-

justable relative to said platform and a lever
operated by movements of said handle and 25
adapted to be engaged with said platform,
substantially as and for the purpose specified.

2. A platform-scale; wings, i , i , secured to
the base thereof and a lever pivotally con-
nected with the scale-body and adapted to de- 30
press the scale-platform in response to lifting
force applied.

3. In a device of the character described,
the platform, h , the swinging frame, C , the
lever, w , and devices for throwing an arm of 35
said lever into contact with said platform.

4. The spring scale-balance, its platform,
easing and its index in combination with the
swinging frame; the vertically-movable lift-
ing-handle, and the lever, w , operated by 40
movements of said handle.

WILLIS H. JORDAN.
